UNITED STATES PATENT OFFICE

2,520,820

SAFETY SHUTOFF FOR OIL TREATERS

Elmer R. Williams, Tulsa, Okla.

Application May 16, 1945, Serial No. 594,124

3 Claims. (Cl. 122—504)

1

The invention relates to safety cut-offs for oil treaters, and has for its object to provide means whereby the supply of oil emulsion to the treater, as well as the supply of fuel to the burner, will be cut-off in case of a fracture or rupture of the wall of the combustion chamber or the burning out of a tube, thereby preventing the ignition of the emulsion and the consequent danger of an extensive fire where the flaming emulsion flows from the treater.

A further object is to provide an auxiliary float controlled means in connection with the treater and overflow system whereby the supply of emulsion will be shut off if the liquid level reaches a dangerous low position in the treater.

A further object is to provide, in connection with the emulsion intake line, a weight controlled diverting valve, which, under normal operating conditions, will allow the flow of emulsion to the treater, and which diverting valve will divert the flow of emulsion from the treater into an emergency by-pass line if there is a flooding of the treater and combustion chamber, incident to a rupture thereof.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a side elevation of a portion of a conventional form of oil treater, showing the safety device applied thereto.

Figure 2 is a side elevation of the treater, storage tank and pipe line, and showing the diverting valve and fuel supply valve closed.

Referring to the drawings, the numeral 1 designates the treater. It is to be understood that the safety device may be applied to an oil treater or heater and applicant does not limit himself to either. For purposes of description the device will be referred to as a treater.

The treater 1 is of conventional type and has therein a fire box 2 having a combustion chamber 3 and tubes 4 through which the products of combustion pass to the stack 5. Gas is usually used as the fuel, and this is connected to the combustion chamber 3 through a gas supply pipe 6 and burner 7. The supply pipe 6 may lead to any suitable source of gas supply. Interposed in the supply pipe 6 is a conventional form of reciprocating cut-off valve 8, operated by hinged-

2

ly mounted weight lever 9 having a fluid receiving receptacle 10 on one end and counterbalancing weights 11 on the other end. The receptacle 10 has a loose sliding mounting at 12 on a downwardly extending pipe 13, which catches the overflow of emulsion from the combustion chamber 3 in case the fire box 2 is fractured, or the tubes 4. This is usually caused by the burning out of the tubes, or the wall of the fire box, and at which time the oil from the main chamber of the treater flows into the bottom of the combustion chamber and may become ignited if there is sufficient flow to raise the oil level in the fire box 3 to an elevation where it will be ignited by the gas burner. When sufficient emulsion flows into the receptacle 10 filling the same its weight is increased to a point where it overbalances the weights 11 and the valve 8 is closed, thereby cutting off the supply of fuel to the burner and preventing a fire hazard.

A horizontal pipe 15 is connected to the downwardly extending pipe 13 and is adapted to also supply liquid to the fluid receptacle 16 after the burner is cut off by the filling of receptacle 10. Receptacle 16 controls the diverting valve 17 through the medium of a weight actuated lever 18. Oil emulsion is supplied to the treater through the supply pipe 19, and the emulsion normally passes through the diverting valve 17, and pipe 20 to the bottom of the treater. Pipe 15 is provided with a downwardly extending discharge pipe 21 which extends loosely into the upper end of the receptacle 16, hence it will be seen that the diverting valve 17, as well as the fuel supply valve 8 will be substantially simultaneously closed upon a flooding of the combustion chamber. The closed position is shown in Figure 2, and both positions are shown in full and dotted lines in Figure 1.

Under normal operation the treated oil passes from the upper end of the treater 1 through a tank line 22 to a storage tank 23, and this line 22 is provided with a back check valve 24, the purpose of which will presently appear. Connected to the tank line 22 on the storage tank side of the check valve 24 is an emergency by-pass pipe 25, and the pipe 25 connects to the diverting valve 17. When the diverting valve 17 is closed, incident to a rupture in the fire box or tubes 4, the supply of oil emulsion is cut off from the treater and is diverted through the by-pass pipe 25 to the tank line 22 and is discharged into the storage tank. It will be noted that the oil can not pass to the treater as it will be blocked by the check valve 24. As an additional safety device the treater is

provided with a float controlled valve 26 above the tubing 28, and disposed in the chamber of a casing 27, and this is designed to cause the cut off of the fuel to the burner and to close the diverting valve if the liquid level should fall to a dangerous elevation in the treater. When this happens oil will pass downwardly through the pipe 28 into the pipe 15 and will flow to both receptacles 10 and 16, hence it will be seen that the possibility of flooding and the spreading of fire is obviated, and the device overcomes one of the difficulties and dangers now experienced with oil treaters and heaters.

The weighted levers 9 and 18 which carry the receptacles 10 and 16 are partially counterbalanced so that a small amount of liquid accumulated in the receptacles 10 and 16 will rock the levers and close the valves 8 and 17.

The invention having been set forth what is claimed as new and useful is:

1. The combination with an oil treater having a fire box therein, a fuel burner within said fire box, a fuel supply pipe leading to said fuel burner, an emulsion supply pipe leading to and discharging into the lower end of the treater, a discharge pipe leading from the upper end of said treater, a by-pass pipe connecting the discharge pipe and supply pipe of the treater, of a diverting valve in said supply pipe between the by-pass pipe and the treater, a cut-off valve in the fuel supply pipe leading to the burner, an overflow discharge pipe leading from the fire box, a rock lever controlling the operation of the fuel supply valve, a rock lever controlling the shifting of

the diverting valve, said overflow pipe from the fire box discharging into a receptacle on the fuel supply valve lever, a receptacle carried by the diverting valve rock lever and a pipe connecting the fire box discharge pipe and extending into the receptacle carried by the diverting valve rock lever.

2. A device as set forth in claim 1 wherein the fuel supply control valve is substantially counterbalanced, said diverting valve lever also being substantially counterbalanced whereby both valves will be maintained open under normal operations and will be closed and shifted upon flooding within the fire box.

3. A device as set forth in claim 1 including a float controlled liquid level valve carried by the treater above the fire box, and a discharge pipe in connection with said float controlled valve, said discharge pipe discharging into the overflow pipe connecting the fire box discharge pipe and discharging into the fuel valve lever receptacle and into the diverting valve receptacle, for operating said valves.

ELMER R. WILLIAMS.
